AUTOMATIC TELEPHONE-EXCHANGE SYSTEM.

1,107,138.

Specification of Letters Patent.

Patented Aug. 11, 1914.

Application filed September 18, 1905. Serial No. 279,031.

To all whom it may concern:

Be it known that I, EDWARD E. CLEMENT, a citizen of the United States, residing at Washington, in the District of Columbia, have invented a certain new and useful Improvement in Automatic Telephone-Exchange Systems, of which the following is a specification, reference being had therein to the accompanying drawing.

10 My invention relates to automatic telephone exchange systems, and has for its object the improvement thereof in the matters of efficiency and cost, the latter both in installing and operating.

15 I attain my object in a manner which will be hereafter pointed out.

Heretofore, various more or less complicated contrivances have been required at the subscriber's station to produce impulses over one line-wire or the other and ground, or both at once and ground, and to regulate the duration and arrangement of these impulses or both. I reduce the subscriber's sender to its simplest possible form, a simple make and break of the circuit being all that I use, all current changes moreover constituting the controlling impulses, being of the same length, and all apparatus positive acting. I differentiate between the switching impulses and those which I may denominate control impulses by means of time element apparatus; but this is so certain in its action as to remove the idea of marginal working. I believe I am the first successfully to operate automatic systems in the manner described by merely making and breaking the metallic or other circuit, and I shall claim the same accordingly.

Heretofore it has been customary to provide each line at the central office with a switching device by which it could be connected through associated devices with other lines. In large exchanges this means that assuming the number of subscribers' lines is 45 100 per cent., under ordinary conditions there would be at least 120 per cent. of switches, and according to the best practice there would be 100 contacts in each switch. I reduce the total number of 50 switches below the number of lines, providing means whereby the various switches may serve each a number of different lines. Moreover, I provide for means to distribute the calls more uniformly than is now possible.

According to my present invention, each line has a signal relay at the central office by which when it calls multiple answering contacts in a number of what I shall call primary selector switches have their potential raised, and thereupon the first primary selector to reach one of said contacts in its constant revolution, stops upon it and thereby connects the line to a chain of automatic switches which may be of any required arrangement or pattern. The operation of my primary selector switch is identical with that of an operator. The latter sticks a plug in answering a call, thereby energizing the cut-off relay, and connecting the line with whatever apparatus is in the cord-circuit. My primary selector lands a contact or sticks a plug, preferably the latter, thereby energizing the cut-off relay, and connecting the line with the switching apparatus.

A very important feature of my invention is this, that it can be applied as a connecting link between manual lines and automatic exchange apparatus of any type. I have illustrated it used in connection with a well-known form of two-wire multiple common battery subscriber's line, and the so-called Strowger automatic exchange apparatus, employed in many large plants with which telephone engineers are familiar; but after reading the following detailed description, it will become obvious that its use is not limited to any particular type of line or exchange. It may be employed in existing automatic exchanges in order to convert them into common battery installations and to simplify the subscriber's line and sub-station apparatus, as well as to increase the capacity of the exchange apparatus; or it may be employed in connection with existing manual systems to replace the central office equipment with automatic switches or to increase the capacity.

The invention is illustrated in the accompanying drawings, in which—

Figure 1 is a diagram showing a subscriber's line and a primary selector by which it can be picked up when calling. Fig. 2 is a complementary figure to Fig. 1, showing first and second selectors of the Strowger type, with a connector therefor. Fig. 3 is a diagram showing the same circuit as Fig. 1, but a modified form of primary selector, which I prefer.

The general scheme may be stated in a

few words: Taking Figs. 1 and 2 together, I will assume subscriber A to be calling, and the primary selector P to be the one which picks him up. He takes his telephone off the hook, whereupon his line-relay at central is energized and connects battery to the contacts, p , in the primary selector bands. Each primary selector is normally driven at a constant rate of speed by means of a shaft 10 and clutch controlled by a magnet. A wiper contact forms a terminal for the winding of a relay which controls the magnet, so that when the switch has brought its test wiper on the terminal contact corresponding to and made alive by the line calling, it stops. A pair of independent wipers are connected to move with the test wiper, and to rest upon the actual line-terminals when the test wiper rests upon the associated test terminal. Hence when the switch stops the line is put through onto the central office connective circuit, and at the same time the latter is closed so as to supply battery current both to the line and to the 25 cut-off relay thereof, whereby the line-relay is removed. The control of the clutch magnet circuit of the primary selector switch is then transferred to a relay on the connective circuit fed with current from the line. As long as the receiver is off the hook at the 30 sub-station, this relay will continue to hold the switch on the line-contact.

The foregoing action takes but a small interval of time, usually but a fraction of a second, and I provide means whereby the subscriber may know that he is connected so that he may go ahead and transmit the number wanted. I prefer to do this by reversing the battery connections normally on 35 the line and those in the switch circuit, providing a polarized indicator at the subscriber's station which is normally concealed, but is displayed as soon as the battery is reversed in making connection with 40 the line. If a sender is employed in which all the numbers can be set up and retained until released, I polarize the controlling magnet so that the signal or a part thereof may come in as soon as connection is effected 45 to the line. Such a device is shown for instance in the patent granted to E. A. Faller, 757,031, April 12, 1904. By polarizing the magnet and arranging the contact devices in a manner well understood by those familiar with the art, it might be used in the 50 present system. Its use is optional, however, and for the sake of simplicity as well as because the sending device in itself forms no part of the present invention, I do not 55 illustrate it, preferring to show a simple key.

Having received the signal showing that he is connected, or rather that his call has been answered at central, the subscriber 60 needs to send the number wanted, thereby

operating the switches at central to connect his line through to the line wanted.

The essential features of my invention are found in Figs. 1 and 3. Referring first to Fig. 1, the substation A is provided with the usual transmitter, receiver and switch-hook, which when up cuts in the talking set and when down cuts in the ringer Q. In addition, I provide the low-wound signal magnet Q, controlling the target which announces the answer to the call, and the key K for breaking and making the circuit, both being in series with the talking set. The line-wires 1-2 pass to the contacts or armatures n , n' of the cut-off relay N, and thence normally to the wires 5 and 6 leading respectively to the line-relay M and to ground. The relay is connected on the other side by wire 7 to the battery, B, which preferably supplies current for all purposes. The local circuit 8 controlled by the line-relay M terminates in a switch 9 normally resting upon a contact connected by wire 10 to the bank test contacts p in a set of the primary selectors P. The switch 9 represents one of the arms of a gang switch by which a given set of lines may be shifted during the busy hour to wires 11, 12 and 13, leading to bank contacts in other groups of primary selectors. This is a purely optional provision, but shows how flexible the system is. When the cut-off relay N is energized it disconnects the armature n , n' , from the line-relay and ground and connects them to the wires 3 and 4 leading to the talking contacts p' in the primary selector banks. The pair of talking contacts p' , associated with each line, bear a fixed relation to the test contacts p in each switch.

The selector switch has a spindle, p^2 , carrying insulated contact arms or wipers, p^3 , p^4 , p^5 , adapted to be rotated around the spindle continuously, and to sweep over the bank contacts p , p' of the various lines. The spindle is kept rotating by means of a clutch connection with a shaft P', shown as driven by a belt, P''. The clutch is shown at P'', having a member, p^6 , fixed on the shaft, P', and an interlocking member, p^7 , splined on the spindle, p^2 . This is controlled by the forked end of an armature lever, o, controlled by an electromagnet, O, associated with the selector. A fixed stop, p^8 , is supported on the frame of the switch in the path of the movable member or collar of the clutch, so that when the magnet pulls down the lever o against the tension of the spring, o', the clutch member, p^7 will not only be disengaged from the shaft member, p^6 , but will engage the stop, and the further rotation of the spindle is thereby prevented.

The wiper, p^3 , is carried on a ring upon which rests a contact brush, p^9 , connected by a wire 14 to the relay S and ground. Wiper, p^4 , is carried by a similar ring upon

which rests a contact brush, p^{40} , forming the terminal of a wire, 15, corresponding to the tip conductor of an ordinary cord-circuit. Wiper p^5 is carried by a similar ring upon 5 which rests a brush, p^{50} , forming the terminal of a wire 16, which corresponds to the sleeve conductor of an ordinary cord-circuit. These two wires corresponding to the tip and sleeve conductors of a cord-circuit, 10 constitute the primary portion of the talking circuit, and terminate in condensers, C, from the other side of which wires 21 and 22 pass to the first selector switch of an ordinary automatic set, constituting in fact 15 the so-called vertical and rotary wires, respectively, of said switch. The wire 15 is normally interrupted at contacts d^2 , d^3 of a solenoid relay D' with which it is connected through the branches 17-18. Wire 16 is similarly normally interrupted at contacts 20 d^4 , d^5 of the same relay, with which it is connected through the branch wires 19 and 20. The core, d^{11} , of this relay is normally 25 down or retracted, maintaining these contacts open, and the winding of the relay is connected on one side by the wire 23 to ground, and on the other side by the wire 24 to the wires 25 and 26, the former passing to a front contact of the test relay S and the latter to a front contact of the supervisory 30 relay S'. Armature s of relay S is connected to the battery wire 7 by means of the branch 27; and the armature s^3 of the relay S' is connected to the battery wire 7 through 35 wire 28, leading to the front contact of relay S², whose armature s^2 goes to battery by way of the wires 29 and 30. When the switch is connected with a line the relay S² retains current as long as the connection 40 lasts, controlling the battery supply to the switch magnets at such time. The branch wire 34 is tapped off from the wire 28, receiving current as long as the relay S² is 45 energized, and conveying it to the spring d^9 of the solenoid relay D'. While the relay is deenergized, all its springs are separated except d^7 , d^8 and d^9 , which are maintained in contact, connecting the battery wire 34 with the wires 35 and 36, leading from springs 50 d^7 and d^8 to the vertical and rotary wires 21 and 22. The solenoid relay D takes its current through wire 32, and momentarily closes together springs d , d' in pulling up or letting go. These springs are connected, 55 respectively, to the wire 37, leading from wire 22, and the wire 38, leading from the wire 24, which latter takes current from the wire 28 when the relay S' is energized.

The magnet O, which controls the starting and stopping of the primary selector, is connected on one side to ground and on the other through the wire 39 to the spring d^{10} of the solenoid D'.

Having thus described the essential features of the apparatus wherein my invention

particularly resides, I will now pass to a set of automatic selector switches with which it is intended to work conveniently, translating mere makes and breaks in the metallic circuit of the line into whatever impulses, over whatever branches, are required. These switches are shown in Fig. 2, being designated respectively by the letters, F, and F'. They are of the types shown in the Keith and Erickson Patent 70 815,321, granted March 13, 1906. The wires 21 and 22 which are broken at the right-hand side of Fig. 1, commence again at the left-hand side of Fig. 2 and pass to switch-arms 47 and 48, which normally rest upon contacts forming terminals of the wires 40 and 42, leading respectively to the relay magnets V and R, which are called the vertical and rotary relays of the first selector switch F. Impulses coming over the 80 wire 21 when the switch is normal affect the relay V, passing through its windings to ground, while impulses going over the wire 22 affect the relay R, passing through its windings to ground.

The switch F comprises a rotary spindle f, carrying insulated contact wipers w , w^2 , which are adapted to sweep over a set of contacts w' and w^3 , constituting the terminals of trunk conductors 210 and 220 passing to second selector switches. The spindle f also carries an insulated test and release wiper w^0 , which sweeps over a set of contacts w^{10} , corresponding to the contacts of the talking circuits w' and w^3 , but forming 90 the terminals of test and release circuits 60 for the second selector switches.

The vertical relay V controls a magnet V', called the vertical magnet, which is provided with a ratchet mechanism to step the spindle 105 f up to the desired row of contacts, w' , w^3 , w^{10} , these contacts being arranged in horizontal rows of ten each. The rotary relay R controls what is called the rotary magnet R', which is fitted with a ratchet mechanism by which it can turn the spindle f, one step at a time, making its wipers rest upon one set of contacts after another in the respective rows selected. The magnet 110 R' is automatic in its operation, that is to say it carries an insulating wedge on its armature, shown at r' , which acts to make and break its own circuit as it vibrates. The armature also carries a projecting lug or stud, r^{10} , which in operation impinges 115 against the armature t of the magnet T⁰, whose function will appear in the statement of operation.

U is the release magnet, equipped with an armature lever, which upon being attracted will lift the retaining pawls off the ratchets of the spindle f, permitting the latter to be turned back to zero and dropped to its normal position by a suitable spring.

T is the test and release relay, connected 130

on the one side to the switch-arm 49 and on the other side by wire 50 to the wiper w^0 . In testing, the arm 49 is on the middle contact, connecting the relay T back through wire 52 to the spring-contact r of the rotary relay R, which at the moment of testing is energized so as to render the relay T at that moment active.

The switch-arms 46, 47, 48 and 49 are mounted as a unit and moved together, one step at a time, being all set back into the position shown in the drawing when the magnet U restores the switch to its zero or inactive position, and being thence released step by step by means of an escapement carried by the armature t of the relay T^0 .

The second selector switch F', and its circuits, are identical in all essential particulars with the first selector and its circuits. The vertical and rotary relays in this switch are marked V^2 and R^2 , the vertical and rotary magnets are marked V^3 and R^3 , the private or controlling relay is T^2 , the test and release relay is T' , and the release magnet is U' . The switch wipers are marked w^4 w^6 and w^{10} , while the trunk terminals for the connector groups are marked w^6 , w^7 and w^{10} . The circuits bear the same numbers as their corresponding wires in the first selector, each with a naught added. Thus, the trunk-wires are 210 and 220, the side switch-arms are 460, 470, 480, and 490, etc.

It will be observed that the vertical and rotary relays and magnets are cut off in the last step of the side switch-arms heretofore described, leaving a clean talking circuit. In the connector switch F^2 , to which we now come, this is not so. This switch is of the type shown in the Keith and Erickson Patent 815,176, granted March 13, 1903. The vertical and rotary relays V^4 and R^4 are both intended to work the switch spindle step by step, and serve during connection to afford control over all the switches in the series, working through the back release wires and the relays T, T', etc. From its multiples in the banks of the second selector switches, the wire 61 comes into the connector switch and terminates at a condenser C', while the wire 62 terminates at a similar condenser. From 61 a branch 63 extends to the relay V^4 , which is grounded on the other side. From 62 a branch 64 extends to the relay R^4 , which is grounded likewise on the other side, both these branches being permanent.

The vertical relay V^4 controls a local circuit 78, passing from the spring v , to a pair of contacts on the relay T^3 to the switch-arm 67. Remembering that the arms 67, 68, 69 and 70 all move together as controlled by the escapement of the magnet T^3 , the normal position of arm 67 puts the wire 78 into connection with the wire 80, thence to the vertical magnet V^5 , which raises the

spindle f step by step to select the desired row of line-contacts; and this magnet is connected to battery by the wire 74. With the switch-arm 67 in the second position, the wire 78 is put into connection with the wire 79 and thence with the rotary magnet R^5 , fitted to turn the spindle f step by step, not after the fashion of the selector relays, R' and R^3 , but only as energized for each step separately. Thus, the spindle may be turned around to a particular contact in the selected row. With the switch-arm 67 in its third position the wire 78 is connected to the wire 81 and so to the ringing relay Z, which controls the contacts z , z' , z^2 , z^3 , z^4 and z^5 , these contacts being included in the two sides 65 and 66 of the talking circuit wires, terminating on the switch-arms 68 and 69, open during selection, but at the last stage, when the subscriber wanted is actually connected, closed to the wires 71 and 72 leading to the talking circuit wipers w^8 and w^9 . When the magnet Z is energized it works its contacts just as an ordinary manual ringing key does, breaking the conductors 65 and 66, and connecting the forward ends to the generator G.

U^2 is the release and test magnet. X , X' are bridged battery or retardation coils in the battery supply circuit to the called line. The functions of these and other parts will appear further from the statement of operation.

It will now be possible to comprehend the operation of my invention as embodied in the apparatus illustrated in Figs. 1 and 2.

I have not shown the substation and line of the subscriber to be called, but these are supposed to be the same as the substation A and line 1-2. We will assume the subscriber A to be calling. He takes his receiver from the hook, closing the line-circuit through his talking set as follows: B, 7, M, 5, n , 1, K, switch-hook, talking set, Q', 2, n' , 6 and ground back to battery. The relay M becoming energized pulls up its armature and closes a circuit from battery to the contact p in the primary selector banks, as follows: B, 7, m , 8, 9, 10, p . The contacts p thus having their potential raised, when any one of them is touched by the wiper p^3 of a primary selector switch in its revolution, a circuit is closed from the battery to the relay S, through 7, 8, 9, 10, p , p^3 , p^{10} and 14. The relay S thereupon pulls up its armature s and closes the circuit of solenoid D': B, 7, 27, s , 25, 24, D', 23 and ground back to battery. The solenoid thereupon instantly pulls up its core, the arrangement being such that the core will pull up very quickly, but relax and drop down very slowly. This may be secured in a considerable degree by simply making the core fit rather closely in its channel. The current in the windings I find brings it up

then very sharply, while the comparatively small force exerted by gravity pulls it down against atmospheric resistance very slowly. To increase the difference I use a check valve 5 in the top of the spool of the solenoid, arranged to open outwardly. When the core rises, this permits the confined air to escape quickly, but when the core falls the air is admitted very slowly and the core therefore 10 is equally sluggish in falling. As soon as the core d^{11} is pulled up it opens the springs d^7 , d^8 and d^9 , which are normally closed together, and closes together the springs d^6 , d^7 and d^9 , d^{10} , on the one side, with d^4 , d^5 15 and d^2 , d^3 on the other side. The effect of this is to complete the continuity of the wires 15 and 16 from the contacts p^{40} and p^{50} to the relays S' and S^2 , so that current from the main battery B will at once flow out over 20 the line-circuit as follows: B , 7, 30, S^2 , 20, d^5 , d^4 , 19, 16, p^{50} , p^5 , p' , 4, N , ground and back to battery; then as soon as this causes 25 the energization of relay N , in parallel therewith from 4 to n' , 2, Q' , talking set, switch-hook, key K , 1, n , 3, p' , p^4 , p^{40} , 15, 18, d^2 , d^3 , relay S' , ground and back to battery. The relay S^2 is energized by the same current as and hence simultaneously with the cut-off relay N , putting current on the 30 wire 28; the relay S' is energized as soon as the cut-off relay N acts, pulling up its armature and keeping the battery on the wire 24 through the branch 26, this being necessary because the relay S is cut off and ceases to 35 supply current through the wire 25. This occurs in the following manner: The actuation of the cut-off relay N disconnects the wires 5 and 6 from the line-wires 1 and 2, whereupon the line-relay M of course loses 40 current, the circuit 7, 8, 9 and 10 is opened, and hence relay S is cut off.

In drawing up its armature and closing the springs d^8 and d^{10} , together, the solenoid D' completes the operating circuit of the 45 stop magnet O , as follows: B , 7, 30, 29, s^2 , 34, d^9 , d^{10} , 39, O and ground back to battery. The magnet O pulls down its armature and the lever o , disengages the upper part of the clutch member p^7 from the shaft plate p^6 , 50 and brings the lower face of the clutch member against the stop p^8 . I have shown both faces of the clutch member serrated to insure a good grip. The stop, p^8 , has an edge which takes into the teeth. The spindle p^2 is thereupon stopped, and the wipers p^3 , p^4 55 and p^5 remain on the contacts p and p' , connecting the calling line 1, 2, 3 and 4 with the conductors 15, 16, and maintaining the connection as long as the line-circuit is closed 60 at the substation, which means as long as the relay S' is energized. It will be understood that while the operations of the several relays have been recounted *seriatim*, they really occur so nearly simultaneously 65 that the wipers, p^3 , p^4 and p^5 have not time

to pass off the line contacts p , p' , of the line calling before the magnet O is energized and the switch is stopped.

It will be observed upon tracing the foregoing circuits that when the solenoid D' 70 pulls up and puts battery through the conductors 15 and 16 to line, this battery is reversed in direction from that normally on the line. Hence the polarized magnet Q' at the substation will reverse its armature 75 upon the position shown, raising the target and indicating to the subscriber that his call is answered and switches placed at his command. He then proceeds to manipulate the key K so as to connect himself with the 80 line wanted.

I preferably provide a sufficient number of primary selectors for each group of lines so that each line may have at least ten multiple contacts of each of the sets p and p' . 85 These contacts are either identical in every switch as to their angular position, (in which case the wipers p^3 , p^4 and p^5 must be displaced one step in each succeeding switch) or the contacts of the same line may be displaced and set in each succeeding switch, 90 and the wipers in all the switches of a set may then have the same angular position with relation to the shaft p^2 .

The solenoid D has no part in the action 95 of selecting the line and stopping the switch. Its function is in transmitting the impulses to the automatic switches. Assume that subscriber A desires to converse with subscriber No. 2468. He first taps the key K twice, 100 each time breaking the circuit and quickly making it again. He then permits a short interval to elapse. The first short break causes the relay S' in Fig. 1 to let go its armature, whereby for a brief instant current is transmitted over the following circuit: B , 7, 30, 29, s^2 , 28, s^3 , 31, 32, D , 23, and ground. At the same time current is sent over a second branch from the wire 31 by way of 33, d^6 , d^7 and 35 to the wire 21. This 110 is the vertical side of line, and the pulse of current proceeds to the first selector switch in Fig. 2, which will be referred to presently. That portion of the current which reaches solenoid D causes it to pull up quickly, closing the springs d , d' together in passing, but it should be noted that while this closes the circuit 37, 38, it does not produce any effect because battery is disconnected from the wire 26 and hence from the wire 24, because at 115 the instant the solenoid pulls up the armature s^2 of the relay S' is back. It is true that this also takes current off of the solenoid D' , but the break is very short, and while either solenoid will pull up on a momentary 120 impulse, neither of them will fall back far enough to perform any work except on a long change in current. Hence the solenoid D' is unaffected by the short number 125 impulses coming over the line. Both solenoids 130

now have their cores attracted, and so long as the subscriber is sending short breaks, thereby oscillating the armature s^3 back and forth, just so long will both solenoids hold up. Each closure of the armature s^3 on its back contact sends a pulse of current to the wire 21 by the path already traced, so that in calling 2468 two breaks being made, two pulses of current will be sent, and then as the subscriber leaves his line circuit closed, the relay S' will continue to hold up, and the solenoid D , being deprived of current for a considerable period, will let its core retract far enough to close the springs d , d' and send a single pulse of current to the wire 22 by the following path: B, 7, 30, 29, s^2 , 28, s^3 , 26, 24, 38, d' , d , 37, and 22. The wire 22 is the socalled rotary wire of the first selector switch in Fig. 2. Thus two short breaks produced in the metallic circuit have been translated into two current impulses on the vertical side 21, and one impulse following the group, on the rotary side 22. In a similar manner the next number, 4, is transmitted by making four short breaks at the key K, which are translated into four impulses on the vertical side 21, followed by one impulse on the rotary side 22. Each succeeding group of short breaks is translated in the same way, all that the subscriber has to do to send the number I have mentioned being to tap the key twice, then four times, then six times, and finally eight times, leaving a reasonable interval between the groups. Here the peculiar features of my invention end. So far as the present application is concerned, any desired form and arrangement of switches and circuits may be adopted, and it will be found that my solenoids and relay scheme of Fig. 1 will enable any standard switches to be worked merely by the subscriber making and breaking the metallic circuit. I emphasize this because it is exceedingly important for two reasons. In the first place it is undesirable and is now considered bad practice to have any grounds on the lines if they can be avoided; and in the second place I am enabled to apply my present invention to existing common battery systems having metallic circuits by merely supplying a separate box or casing with the circuit breaker K of any desired type, and the signal device Q'. To connect this for operation requires merely that its binding posts shall be interpolated in the talking circuit.

I have shown how by tapping his key the subscriber sends successive groups of impulses over the wire 21, and a single impulse at the end of each group over wire 22. This is all it is necessary to assume or to remember in order to understand Fig. 2. The first two impulses come over the wire 21 and cause the relay V to pull up twice, each time closing the following circuit: battery B, 7,

55, 57, V', 56, contacts of magnet T^0 , 59, v , g , 60, and back to battery. This causes the magnet V' to step up the spindle f two steps, so as to bring the contact wipers w , w^2 and w^0 opposite the second rows of contacts. In these rows are the terminals of trunks 210, 220 and test wires 60, leading to 10 second selector switches of the order of 2000. Following the group of two impulses over wire 21, comes the single impulse from wire 22. This energizes rotary magnet R, which pulls up and closes the following circuit: battery B, 7, 55, T^0 , v , g , 60 and back to battery. The magnet T^0 thereupon pulls up, breaking the circuit 56-59 of the vertical magnet V', and making the first movement of the escapement so that upon the retraction of the armature t , the side switch arms 46, 47, 48 and 49 are permitted to move one step, whereupon the following circuit is immediately closed for the rotary magnet R': battery B, 7, 55, 57, R', 58, 46, 43 and ground back to battery. The rotary magnet R' thereupon pulls up, its stud, r' , breaks the circuit and it lets go, the stud 90 closes the circuit and it pulls up again, and so on with the following results: Each time the armature of the rotary magnet pulls up, it steps around the spindle f one step, and causes each wiper to pass from one contact to the next, making contact with the succeeding one, however, before it leaves the preceding one. At each movement of the armature of the rotary relay, the armature t of the relay T^0 is kicked up by the stud r^{10} , but released when the wipers come on a fresh contact. That is to say, on the forward stroke the armature t is forced to take the first step toward moving the escapement to release the side switch-arms for their last step. Now as the wiper w^0 passes over the successive contacts w^{10} of the different trunks all leading to second selectors numbered 2000, it is hunting for an idle one, and the idea is to have the side switch move a third step when an idle trunk is found. Each contact that is busy has a ground on it, as will presently appear. Hence, if in its first movement the wiper w^0 finds such a grounded contact, it will at once close the following circuit: Battery, 7, 55, T^0 , 52, 49, T, 50, w^0 , w^{10} , and ground back to battery. As stated, on the first part of the stroke the armature t is mechanically held up. Current flowing in the circuit I have traced holds it up in the second part of the stroke of the rotary armature, so that after the armature t is once kicked up, it stays up, held alternately by the stud r^{10} and by its own magnet T^0 , until an idle or underground contact w^{10} is reached. When this happens the armature t falls back, and its escapement permits the four switches 46, 47, 48 and 49 to take their last step. Switch 46 cuts off the rotary magnet 120 125 130

and stops the machine instantly. 47 and 48 cut off the vertical and rotary relays V and R, and complete the talking circuit: 21—44, 22—45. 49 cuts off the magnet T^o, 5 and closes the circuit of magnet T through wire 51 to ground, thus putting a ground on the wiper w^o and all the multiples w¹⁰ of the contact on which it rests, rendering the trunk "busy," so that no other switch 10 can get in. It is proper to say that the magnet T will not work on the test current through any relay T^o.

We now have at the end of the first group of two impulses, the wires 21 and 22 extended respectively as follows: 21, 47, 44, w, w', 210, 470, V² and ground; 22, 48, 45, w², w³, 220, 480, R² and ground. In other words, the circuit has been extended into the second selector switch F' and the relays V² 20 and R² have been substituted for those of the first selector. We now have the second group of four impulses coming over the combined wires 21 and 210, followed by a single impulse over the combined wires 22 25 and 220. The operation of the relays and other parts is precisely the same in this switch as it was in the first selector, the only differences being in matters of release, etc., which will be touched upon later. The net 30 result of the operation of this switch is to pick out an idle connector switch F², and prolong the circuits as follows: 21—210—61; and 22—220—62. The relays V², R² of the second selector are cut off, and the relays V⁴, 35 R⁴ are substituted therefor, their connections 63 and 64 being permanent, for these two relays are used in releasing the set of switches as well as in selecting. The subscriber now 40 sends six impulses to relay V⁴, each of which causes the same to pull up, operating the vertical magnet V⁵ over the following circuit: battery, 7, 74, V⁵, 80, 67, 78, v, 60 and ground back to battery. The number of the 45 wanted line is 68, so that the six impulses working in this way through magnet V⁵ step up the spindle f to the sixth row of line-contacts. The subscriber then sends a single impulse over the wire 62 to the rotary relay R⁴, which pulls up and closes the following 50 circuit: battery B, 7, 75, 77, T³, r, 60, and ground back to battery. The magnet T³ pulls up and then lets go, it being observed that there is no rotatory kicker to hold it up in this case. The side switch-arms 67, 68, 69 55 and 70 are therefore stepped around promptly one step. Vertical magnet V⁵ is thereby cut out and rotary magnet R⁵ cut in, but this magnet has no vibrator, being constructed to turn the switch spindle only 60 one step at a time. The subscriber now sends his final number 8 over the wire 61, and the same relay V⁴ responds, each time closing the following circuit: battery B, 7, 74, R⁵, 79, 67, 78, v, 60, and ground back to 65 battery. The spindle is therefore stepped

around until the wipers w⁸, w⁹ and w⁸⁰ rest upon the three contacts belonging to line 68 in that hundred. A single impulse now comes over the rotary side of line, and pulls up the relay R⁴, which closes the following 70 circuit, after testing to see if the line is idle: battery B, 75, magnet T³, r, 60 and ground back to battery. The relay T³ thereupon pulls up, closing the following circuit: battery B, 7, 75, release magnet U², 76, contacts of relay T³, 82, 70, (this being on its second point), w⁸⁰ or w⁸, and to the tip side of the line being tested. Now, if the line wanted, 75 where really testing, is already connected either through a connector switch, as shown in Fig. 2, or through a primary selector switch, as shown in Fig. 1, there will be a ground on the tip side, otherwise not. In the first case, the ground will be through the wire 71, switch-arm 68, wire 65, and magnet X. In the other case it will be through the wire 3, the wiper p⁴, the wire 15, and the relay S'. In either case, if the line is busy the release magnet U² of the testing switch will pull up releasing the same and causing 80 it to return to zero position. In other words, the subscriber does not get on to the line wanted if it is busy.

If the line wanted is not busy, the momentary impulse over the rotary side ceases, the 85 relays R⁴ and T³ let go, and the side switches go the last step, cutting off the working magnets R⁵ and V⁵ entirely, substituting the ringing relay Z through the wire 81 and the arm 67, and completing the circuit of wires 100 65 and 66 through 71 and 72 to the line wanted. In order to ring the wanted subscriber, the next thing is to energize the relay Z, which is ordinarily done by simply breaking the circuit at the calling subscriber's station by means of a push-button. In the present system we cannot do this because a prolonged break would deenergize the solenoid D', and would release all the switches. So I do not provide any special 105 ringing button, but after the line wanted is selected, a succession of taps on the key K is produced by the calling subscriber, and these energize the relay Z, by energizing the relay V⁴. I preferably make the relay Z a 110 solenoid like those shown in Fig. 1, so that the succession of short closures will hold its core up as long as they continue. The energization of this relay opens the springs z, z', z² and z⁴, and closes z' on z² and z⁴ on z⁵, 115 thus connecting the ringing generator G across the wipers w⁸, w⁹. When the called subscriber answers, he derives current for his transmitter from the main battery through the bridging coils X, X'. 120

When the subscribers have finished talking, the receivers are hung up, the metallic circuits being thus opened at the sub-stations. Referring to Fig. 1, it will be observed that this opening at substation A lets 125 130

go the relay S', which cuts off the solenoid D', whose core d'' drops to its normal position shown in the drawing. The springs d', a⁸ and d⁹ therefore come together, and battery is put on both trunk-wires 21 and 22, by the following path: B, 7, 30, 29, s², 34, d⁹, d⁸ and d', through wires 36 and 35. Referring to Fig. 2, these simultaneous impulses over both trunk-wires 61 and 62 energize both relays V⁴ and R⁴ at the same time, closing together the springs v^x and r^x, and the following release circuit: battery, 7, 75, U², 76, r^x, v^x, w⁵⁰, w⁴⁰, T' 490, ground back to battery. Magnet U² releases and 10 stores the connector switch F'; relay T' closes the following release circuit: B, U', contacts of T', 60, w¹⁰, w⁹, 50, T, 49, 51, and ground back to battery. Magnet U' thereupon releases and restores the switch F', and relay T closes the following release 20 circuit: B, 7, 55, U, 54, contacts of T, ground back to battery. Magnet U thereupon restores the switch F. All the automatic switches are therefore restored.

25 As soon as the solenoid D' resumed the condition shown, in Fig. 1, the circuit of magnet O was broken at the springs d⁹, d¹⁰, with the result that this magnet let go, and the spring o' pulled up the lever o, releasing 30 the clutch member p' from stop p⁸, throwing it onto the shaft disk p⁶, whereupon the switch wipers p³, p⁴, and p⁵ are again rotated. As soon as they pass off the contacts p, p', the relays S² and N are dissociated, 35 their circuit through the branch 19-20 of the conductor 16 having already been broken by the solenoid D'.

In Fig. 3 I have shown a preferred modification of the primary selector switch P, all other parts being unchanged. In this figure the shaft P' is constantly revolving, and I use a revolving arm having a solenoid with a movable core, clutched to the shaft by the inner end of the core p' engaging a notch p⁶, and the outer end adapted to engage any one of a succession of openings in a stop ring or jack ring p⁸, which is concentric with the shaft and has its openings respectively opposite corresponding groups 45 of line and trunk contact springs p', p⁴, p⁵, the springs p⁴, p⁵ are preferably integral throughout the circle, but cut in combs, with one pair of individual members opposite each pair of line-contacts p'. The solenoid has two windings, S¹⁰ and O¹⁰, which 50 perform the same functions as the two magnets S and O, in Fig. 1. In other words, as soon as the contact p³, corresponding to the same part in Fig. 1, comes upon a charged 55 contact, the winding S¹⁰ takes current and pulls in the solenoid core p', loosing the arm from the shaft and simultaneously projecting its forward insulated end through the jack ring p⁸ between the springs p⁴, p⁵, 60 thereby pressing them out against the line- 65

contacts p' of the calling line, and stopping the arm. The insertion of the plug in the line-jack acts just as it would in a manual system. Relays S² and N get current, and S' pulls up, whereupon solenoid D' gets 70 current, and the rest of the operation is the same as that heretofore described. After the wire 10 is disconnected from battery, which is necessary because otherwise the contact p would continue to test "busy" to 75 other switches, the core p' and its plug are held up by the winding o¹⁰, connected for convenience through spring p⁰ and the solid ring contact thereof through wire 39 to the contacts of solenoid D'. 80

It will be noted in Fig. 1 that the branch wire 31 is connected through the spring d⁸ and its companion d' with wire 35 to one side 21 of the talking circuit, during conversation. This puts a ground on one side 85 through the lamp s', which in practice would not be permissible. In Fig. 3 I have shown how this is avoided by providing the wire 31 with a separate terminal point, which is left open when relay S' is energized, that is during conversation.

In the claims to follow I shall use the expression "a set of switches" to mean a complete connective outfit from the primary selector P, of whatever type, to the connector F', of whatever type. In a small exchange, the primary selector and connector might be the only two switches, and they might be in one structure, while in a large exchange a set would include selectors F, F', etc., as 95 well as a connector. 100

In Fig. 3, I have shown a ratchet mechanism P' for the shaft P', controlled by the line relay M through a starting wire 100, connected when the relay is energized to 105 the commutator M'. The wire 10 can be connected to the commutator and the latter direct to the wire 100, however, as I have above stated, thus dispensing with one pair of contacts for the relay. 110

I do not herein claim broadly automatic switches controlled by relays having different time constants or through impulses of varying electrical characteristics transmitted over the subscriber's metallic line circuit (including the two sides of the line in series or other circuit normally free from ground connections) inasmuch as the same is now being claimed in my application Serial No. 291,097, filed December 9, 1905. 115 120

Having thus described my invention, what I claim and desire to secure by Letters Patent is:

1. In a telephone exchange system, subscribers' lines each having means to make 125 and break the metallic circuit, a central current supply, an automatic connective apparatus comprising a selecting and calling set of switches and a primary selector switch, answering line terminals in the lat- 130

- ter with a switch member engaging the same and means to drive it, a relay associated with each line, a magnet controlled thereby and controlling the primary selector switch 5 when the same engages the line terminals, stopping the switch thereon, controlling magnets for the selective switches, and translating relays placed under the line-control by the primary selector, to control the said 10 switch magnets, substantially as described.
2. In a telephone exchange system, a plurality of subscribers' metallic circuits each provided with sub-station talking and signal-receiving apparatus and means to make 15 and break the circuit in accordance with a code, and central office connective apparatus comprising the following instrumentalities: a line relay M and a cut-off relay for each line, a primary selector switch P and means 20 to drive the same, line terminals p, p' , therein, a controlling magnet therefor, a trunk circuit 15-16, 21-22, and selector switch-circuits connected to said trunk with controlling magnets V, V', R, R', etc., connect- 25 ed thereto, and relays S', D, D', the first responding to all makes and breaks in the metallic circuit, the second to breaks only, and the third to makes only, together with connections for the switch-magnets controlled 30 by said relays in response to the makes and breaks in the subscriber's line, substantially as described.
3. In a telephone exchange system, subscribers' lines, a primary selector switch 35 comprising a normally continuously rotating spindle carrying terminal wipers, contacts for the lines in said switch, a set of automatic selective switching apparatus a trunk line constituting a talking circuit 40 from said primary selector switch to said automatic selective switching apparatus, and means to operate the primary selector switch to stop the rotation of said parts and to effect a connection of the contacts 45 of a calling line with said trunk and the selective switching apparatus, substantially as described.
4. In a telephone exchange system, subscribers' lines, a primary selector switch 50 having normally rotating parts, contacts of the lines in said switch, a set of connective automatic switches, a trunk line from the primary selector switch to the connective switches, and means directly controlled by a 55 calling line to cause said normally rotating parts of said primary selector switch to connect the contacts of the calling line for purposes of conversation through itself with the trunk and connective switches, and thence to the line wanted, substantially as described.
5. In a telephone exchange system, subscribers' lines, an automatic connective switch, and primary selector switches, each 60 primary selector adapted to be connected to the automatic connective switch, auxiliary switches arranged in percentage order and associated therewith through which a calling subscriber may connect himself with any other line, line terminals multiplied into 65 the primary selector switches, line controlled actuating means individual to each line to cause the said primary selector switches to make connection with the contacts of a calling line, and means intermediate the primary selector and the adjoining automatic connective switch arranged to permit the subscriber to operate the connective and auxiliary switches, substantially as described. 70
6. In an automatic telephone exchange 75 system, a plurality of subscribers' lines and a primary selector switch containing answering terminals therefor, a movable member for said switch, together with means to drive the same, so as to connect with any line having terminals therein, a centralized source of current supply for the lines, a controlling relay associated with each line, and a controlling magnet for the primary selector, automatic selective switches associated with the primary selector, multiple connecting terminals for subscribers' lines in one or more of said switches, and means located intermediate the primary selector switch and the adjoining automatic selective 80 switches and arranged to be controlled by the subscribers through the primary selector switch for actuating the other switches to continue the connection to the line wanted, substantially as described. 85
7. In an automatic telephone exchange 90 system, subscribers' lines and interconnecting means therefor, comprising automatic switches in permanently connected sets each having answering and calling terminals, additional calling switches with which the calling switches of the sets may connect together with means individually associated with each subscriber's line for directly controlling the answering switches, and means located intermediate the primary selector switch and the adjoining automatic selective 95 switches and arranged to be controlled by the subscribers through the primary selector switch for actuating the other switches to continue the connection to the line wanted, substantially as described. 100
8. In an automatic telephone exchange 105 system, a central office, plurality of metallic circuit lines terminating in said office, a common source of current supply for said lines and means associated with each line for determining the flow of current over the two sides of the line in series, a relay normally associated with each line, a number of connective circuits at the central office less than the number of lines and each provided with an automatic answering switch and one or more 110 automatic connective switches containing line terminals, and circuit connections from the line relays to the answering terminal switches whereby the same may be directly controlled by the lines when calling to effect 115

connection therewith, substantially as described.

9. In an automatic telephone system, a plurality of subscribers' lines and central office connective apparatus therefor comprising selector and connective switches in sets, each set containing a plurality of connective switches arranged in percentage order, said connective switches containing multiplied called line terminals and adapted to be sequentially actuated to establish talking circuits link by link from one switch to another and finally to the wanted line, a number of primary selector switches containing multiplied calling terminals, directly controlled by the lines and adapted when actuated to connect the same with the other selector switches, and means at each subscriber's station for varying the flow of current over the two sides of his line in series to produce groups of impulses varying in number according to a predetermined code, together with translating devices at the central office affected by said code changes in the metallic circuit and acting to distribute current to the switch controlling magnets to actuate the selective switching apparatus to make a connection corresponding to said code changes, substantially as described.
10. In a telephone exchange system, a plurality of line circuits and link connective circuits therefor each having a primary selector switch comprising a movable spindle carrying wipers forming answering terminals of the link, means to drive and means to stop said switch, multiplied answering terminals for the lines in said switch, a relay for each line adapted to initially and directly act upon said switch to bring it into connection with the line when calling, a relay associated with the switch then coming into connection with the line and maintaining the switch in connection therewith as long as the line is in use, and automatic means for completing the talking circuit through the switch to the line wanted, substantially as described.

11. In an automatic telephone exchange system, line circuits, an automatic primary system, a constantly rotating shaft, moving switch parts connected therewith and adapted to be disconnected therefrom for selecting and connecting with a calling line, an automatic connector switch, and relays associated with said primary switch for controlling said connector switch whereby the latter may effect a connection between a calling and a called line through said selector switch.

12. In an automatic telephone exchange system, a plurality of subscribers' metallic circuits without grounds, a number of central office link circuits less than the number of lines, a primary or answering switch adapted to connect a calling subscriber's

line with an idle link circuit, a selector switch constituting an advance terminal for each link circuit, subsidiary switching means whereby each link selector switch may obtain access to wanted lines, a plurality of local actuating circuits for the selector switches, a primary switch trunk extending between the primary switch and the selector switches, and means associated with the primary switch trunk, responsive to impulses over the two sides of the subscriber's line in series, and adapted when actuated to produce changes in said local switching circuits, properly distributed to set, maintain, and finally restore the switches in proper sequence respectively at the beginning, during the continuance, and at the end of each conversation.

13. In a telephone exchange system, a plurality of subscribers' metallic line circuits, a plurality of selective switches adapted to interconnect the lines, each switch provided with a plurality of controlling relays and local circuits, and primary switches with associated relays, adapted first to connect the lines when calling to the selective switches, and second to translate metallic circuit impulses into distributed impulses for the local switch circuits.

14. In an automatic telephone exchange system, a plurality of subscribers' lines and a primary selector switch containing answering terminals therefor, a movable member for said switch together with means to drive the same so as to connect with any line having terminals therein, a centralized source of current supply for the lines, a controlling relay associated with each line, and controlling magnets for the primary selector, automatic selector switches associated with the primary selector, multiple connecting terminals for the subscribers' lines in one or more switches, and means comprising a pair of relays having different time constants of operation controlled through the primary selector switch for actuating the other switches to continue the connection to the line wanted, substantially as described.

15. In a telephone exchange system, a plurality of metallic or two-wire line circuits, primary selector switching means and central office connective circuits and apparatus associated therewith, local circuits and auxiliary apparatus for said connective circuits and apparatus, and means associated with the primary switching means, responsive to current changes in a metallic line circuit and adapted to translate the same into properly distributed current impulses directed to the several central office circuits and apparatus for the proper operation thereof, substantially as described.

16. In a telephone system, telephone lines, trunks; automatic switches, each trunk terminating in the wipers of an automatic

switch; the said lines being multiplied through a plurality of said automatic switches and appearing as waiting contacts in said automatic switches, and each of said 5 automatic switches having a wiper shaft carrying the wipers of that switch; an auxiliary conductor for each line and terminating in waiting contacts associated with the waiting contact terminals of the line; an 10 auxiliary conductor for a trunk and terminating in a wiper associated with the wipers of the trunk; a source of continuous power; a clutch connecting said source of continuous power and the wiper shaft of the automatic 15 switch of the trunk; and means whereby, by the engagement of the wiper of the auxiliary conductor of the trunk with the waiting contact of the auxiliary conductor of a calling line, the said clutch may be operated to dissociate said source of power from the wiper shaft of the automatic switch, substantially as described.

17. In a telephone exchange system, telephone lines; trunks; automatic switches; each of said automatic switches having a wiper shaft carrying the wipers of that switch; an auxiliary conductor for each line and terminating in waiting contacts in said 20 automatic switches; an auxiliary conductor for a trunk and terminating in a wiper in the automatic switch of the trunk; a source of continuous power; a clutch connecting said source of continuous power and the wiper shaft of the automatic switch of the 25 trunk; and means whereby, by the engagement of the wiper of the auxiliary conductor of the trunk with the waiting contact of the auxiliary conductor of a calling line, the said clutch may be operated to dissociate said source of power from the wiper shaft of the automatic switch, substantially as described.

18. In a telephone system, an automatic switch, fixed contacts and movable contacts 30 in said switch, supporting and driving means for said movable contacts, a source of power for said driving means, a clutch for connecting the driving means with the source of power, telephone line circuits connected to the fixed contacts in the switch, and trunk 35 connections to the movable contacts thereof, together with selective switching means associated with said trunk for connecting the same to wanted lines, and auxiliary circuits 40 and apparatus whereby said clutch normally connects the driving means with the source of power, but is electro magnetically actuated to disconnect the same when the moving contacts rest upon the fixed contacts of a 45 calling line, substantially as described.

19. In a telephone system, a plurality of line circuits, connecting link circuits therefor, an automatic switch constituting a link terminal, having a clutch normally connecting it with a source of power, waiting or

fixed terminals in said switch for said lines, and coöperating link circuit terminals, together with auxiliary electrical circuits and apparatus whereby said automatic switch is automatically isolated from its source of power when the terminals of an idle link are 50 in registry with those of a calling line, and means operable through the line for maintaining such isolation at the will of the calling subscriber, substantially as described.

20. In a telephone system, a plurality of lines, interconnecting link circuits therefor, an automatic switch having a clutch normally connecting it with a source of power, fixed or waiting terminals in said switch for said lines, and coöperating link circuit terminals, together with auxiliary electrical circuits and apparatus whereby said automatic switch is driven until terminals of an idle link and a calling line are in registry, is then 55 automatically isolated from its source of power, and is maintained isolated by means operated through the line and link circuit thus connected, substantially as described.

21. In a telephone system, telephone lines; trunks; automatic switches; each trunk terminating in the wipers of an automatic switch, the said lines being multiplied through a plurality of said automatic switches and appearing as waiting contacts 60 in said automatic switches, and each of said automatic switches having a wiper shaft carrying the wipers of that switch; an auxiliary conductor for each line and terminating in waiting contacts associated with the waiting contact terminals of the line; an auxiliary conductor for a trunk and terminating in a wiper associated with the wipers of the trunk; a source of continuous power; an electromagnetic clutch connecting said 65 source of continuous power and the wiper shaft of the automatic switch of the trunk; and means whereby, by the engagement of the wiper of the auxiliary conductor of the trunk with the waiting contact of the auxiliary conductor of a calling line, the said clutch may be operated to dissociate said 70 source of power from the wiper shaft of the automatic switch, substantially as described.

22. In a telephone system, lines; waiting 75 multiplied contacts forming terminals of said lines; wipers movable over said multiplied waiting contacts; a source of power normally mechanically connected with said wipers through a clutch; means for operating said clutch to dissociate said wipers from said source of power; and means for continuing the condition of dissociation of said wipers from said source of power, said means being adapted to continue such condition dependently upon the calling condition of a then associated one of said telephone lines, substantially as described.

23. In a telephone system, lines; waiting 80 multiplied contacts forming terminals of 70 85 90 95 100 105 110 115 120 125 130

said lines; wipers movable over said multipled waiting contacts; a wiper shaft carrying said wipers; a continuously driven shaft; a clutch normally connecting said continuously driven shaft and said wiper shaft; an electromagnetic controlling means for said clutch whereby said shafts may be disassociated; and means for continuing the disassociation of said shafts dependently upon the continuance of the calling condition of a then associated one of said telephone lines, substantially as described.

24. In a telephone system, telephone lines; waiting multipled contacts forming terminals of the speech-current circuit of said lines; wipers movable over said multipled waiting contacts; a source of power normally mechanically connected with said wipers; a clutch for disassociating said wipers from said source of power; and means for continuing the disassociation of said elements dependently upon the continuance of the calling condition of the telephone line then associated with said wipers through electrical connection of said wipers with the waiting contacts of the line, substantially as described.

25. In a telephone system, telephone lines; waiting multipled contacts forming terminals of the speech-current circuit of said lines; wipers movable over said multipled waiting contacts; a source of power normally mechanically connected with said wipers; a clutch electromagnetically controlled and operating to associate said wipers mechanically with said source of power and to disassociate said wipers from said source of power alternatively; and means for controlling said clutch to continue the disassociation of said wipers from said source of power, said means for controlling being operative dependently upon the continuance of

the calling condition of the telephone line then associated with said wipers through electrical connection of said wipers with 45 waiting contacts of the line, substantially as described.

26. In a telephone system, telephone lines; trunks; automatic switches; each trunk terminating in the wipers of an automatic switch, the said lines being multipled through a plurality of said automatic switches and appearing as waiting contacts in said automatic switches, and each of said automatic switches having a wiper shaft carrying the wipers of that switch; an auxiliary conductor for each line and terminating in waiting contacts associated with the waiting contact terminals of the line; an auxiliary conductor for a trunk and terminating in a 60 wiper associated with the wipers of the trunk; a source of continuous power; a clutch connecting said source of continuous power and the wiper shaft of the automatic switch of the trunk; means whereby, by the engagement of the wiper of the auxiliary conductor of the trunk with the waiting contact of the auxiliary conductor of a calling line, the said clutch may be operated to disassociate said source of power from the wiper 70 shaft of the automatic switch; and other means whereby such operation of the said clutch may be continued dependently upon the continuance of the calling condition upon the telephone line then associated with 75 the trunk through the wipers and contacts of the automatic switch, substantially as described.

In testimony whereof I have affixed my signature in presence of two witnesses.

EDWARD E. CLEMENT.
